[57] CLAIM

The ornamental design for a combined storage and shipping container, substantially as shown.

DESCRIPTION

FIG. 1 is a left side elevational view of a combined storage and shipping container showing my new design; FIG. 2 is a right side elevational view thereof;

FIG. 3 is a front elevational view;

FIG. 4 is a rear elevational view; and

FIG. 5 is a top plan view.

The bottom side of the storage and shipping container, not shown is flat.
